(57) **CLAIM**

The ornamental design for a portion of a computer, as shown and described.

DESCRIPTION

FIG. 1 is a front elevational view of a portion of computer, showing our new design;

FIG. 2 is a rear elevational view thereof;

FIG. 3 is a top plan view thereof;

FIG. 4 is a bottom plan view thereof;

FIG. 5 is a right side elevational view thereof; the opposite side being a mirror image thereof;

FIG. 6 is a front elevational view thereof, the cover of the computer is shown in closed position; and,

FIG. 7 is a left side elevational view thereof, the cover of the computer is shown in closed position.

The broken line drawing of a computer in all views is for illustrative purposes only and forms no part of the claimed design.
